UNITED STATES PATENT OFFICE.

CHARLES HAMMER, OF NEW YORK, N. Y., ASSIGNOR, BY DIRECT AND MESNE ASSIGNMENTS, TO AMERICAN METAL CAP CO., OF BROOKLYN, NEW YORK.

TOP AND SIDE SEAL-CLOSURE.

1,231,881.

Specification of Letters Patent.

Patented July 3, 1917.

Application filed May 26, 1916. Serial No. 99,946.

To all whom it may concern:

Be it known that I, CHARLES HAMMER, a citizen of the United States, residing at New York, in the county and State of New York, have invented certain new and useful Improvements in Top and Side Seal-Closures, of which the following is a specification.

This invention relates to caps or covers for jars adapted to contain various food articles, wherein it is necessary to provide a hermetic closure, and in which it is customary to effect the closing operation or securing of the closure on the jar, in a closed chamber from which the air has been withdrawn, to produce what is usually termed a vacuum seal.

The object of the present invention is to provide a closure of this character that will be securely retained on the jar by the engagement between the cap, and the outer cylindrical side of the jar at its upper end; and which closure can be placed on top of the jar and secured there simply by downward pressure on top of the cap at its margins; without reformation of the cap flange, and without the employment of any dies or chucks, or any means for bringing the flange portion of the closure into holding engagement with the jar, but which closure will be secured on the jar simply by a downward pressure on its top. And furthermore, which is accomplished without the use of any special retaining configuration on the outer engaging face of the jar, the jar having merely a cylindrical side wall adjacent the end, that may be made slightly tapering if preferred.

A further object of the invention is to provide a form of closure provided with the friction retaining means, as set forth, which will cause a hermetic seal to be formed between the end portion of the jar and the closure; and which seal will result from the mere operation of applying downward pressure on the closure to produce the friction locking engagement thereof.

In the accompanying drawing illustrating embodiments of my invention Figure 1 is a plan view of the closure. Fig. 2 is a vertical section at one side of the closure, that rests on top of the jar as first applied. Fig. 3 is a view similar to Fig. 2, but with the closure forced down on the jar to final sealing position. Fig. 4 is a modification of the cap shown in Fig. 1. Fig. 5 shows another form

of cap, as first applied to the jar; and Fig. 6 shows the cap as shown in Fig. 5, in the final sealing position on the jar.

The closure or cap is made of thin sheet metal, and comprises a top portion 12, with a depending flange portion denoted generally by 13. For the purpose of engaging the outer substantially cylindrical wall portion 14 of the jar 15, I provide an inwardly extending rim or bead of annular form on the lower portion of the flange. As shown in Fig. 2, the flange projects inwardly at 16 at substantially a right angle with the flange portion 13; and thereupon the flange is extended downwardly at 17 in a substantially conical form, diverging downwardly. It will be observed that the flange portion 13 above the inwardly extending portion 16, is substantially conical and diverges downwardly. Thereby is formed a ledge or shoulder inside of the cap at the wall 16, and this is well adapted to receive and retain the ring washer 18 that is employed in this style of cap; and which is preferably of a special composition somewhat similar to soft rubber. The washer is of considerable depth relative to its width, and practically engages all the inner wall of the conical flange portion 13. Between the diverging wall 13 and the flat top 12 of the cap, is a curved connecting portion 19.

The rim portion 17 is preferably reinforced by suitable means, such as having its lower edge turned or rolled outwardly to provide a bead 20. But in the modification shown in Fig. 4 this bead is omitted and has no reinforcement; the cap being otherwise identical with that described with reference to Fig. 2.

The jar 15 as shown is provided with its top portion 14 of substantially cylindrical form on the outer wall, and the cap adapted for this size of jar, has an internal diameter at the rim portion 17 adapted to engage the jar at about the middle portion of the diverging conical wall 17, when the cap is first placed on top of the jar, as indicated in Figs. 2 and 5. Thereupon pressure is applied on top of the jar, and will engage it at the highest part on the curved edge 19, and the cap is forced downwardly. This will cause a slight expansion of the rim portion 17 because of its reduced diameter at the upper portion adjacent the shoulder 16, and cause the rim to have a locking engagement

with the wall 14 of the jar, as indicated in Fig. 3. The upper edge of the jar, that is rounded as shown at 21, will engage the inner wall of the washer 18, so that the washer 5 will be compressed, and will be practically engaged by the relatively tapering walls of the jar and the flange wall 13, by a kind of wedge action. This will cause the washer to expand downwardly to a certain extent, 10 to completely fill and close the space between the outer wall 14 of the jar and the walls 13 and 16 of the cap. The end of the jar will also force the washer material upward to extend over the upper edge of the jar, between 15 the same and the rounded portion 19 of the cap, thus forming a top and side seal. By this action the entire space between the side and top of the jar and the adjacent wall of the cap above the rim 17, is filled by the 20 composition washer, as clearly shown in Figs. 3 and 6. But if the jar should have its wall 14 of slightly reduced diameter, it will not have the friction locking engagement with the rim 17. Yet the jar will cause the 25 washer to assume the same shape as shown in Fig. 3, and a top and side seal will still be effected that will securely lock and hold the cap on the jar, and produce a hermetic seal.

30 In the modification shown in Figs. 5 and 6, the cap is formed substantially identical with that of Figs. 2 and 3, except that a slight bead is provided by forcing the lower portion of the conical rim wall 13 outwardly 35 a short distance, forming a kind of bead 22, as shown. When the cap of Fig. 5 is forced down on the jar, the washer 18 will be forced outwardly to fill the space in the bead 22, as shown in Fig. 6. The form of cap shown in 40 Fig. 4 will operate in the same manner as the other caps, but does not have the advantage of the reinforcement by the bead 20.

Having thus described my invention, what I claim is:—

45 1. A jar closure comprising a circular top with an annular side flange having an upper divergent conical part that connects with the top by an arched upwardly projecting portion, the flange having a rim extending abruptly inward at a right angle to the upper conical part and then extending downwardly in a diverging conical form, which 50 rim is adapted to have a friction locking en-

gagement with a substantially straight-walled jar top solely by downward pressure 55 on the top of the closure without reformation of the closure, and a comparatively thin gasket of compressible sealing material held in the closure by the rim, which is compressed on application of the closure to entirely fill the space between the jar side and top and the flange side and top portion above the rim.

2. A jar closure comprising a circular top with an annular side flange having an upper 60 divergent conical part that connects with the top by an arched upwardly projecting portion, the flange having a rim extending abruptly inward at a right angle to the upper conical part and then extending downwardly 65 in a diverging conical form with the margin bent outwardly to form a bead, which rim is adapted to have a friction locking engagement with a substantially straight-walled jar top solely by downward pressure on the 70 top of the closure without reformation of the closure, and a comparatively thin gasket of compressible sealing material held in the closure by the rim, which is compressed on application of the closure to entirely fill the 75 space between the jar side and top and the flange side and top portion above the rim.

3. A jar closure comprising a circular top with an annular side flange having an upper 80 divergent conical part that connects with the top by an arched upwardly projecting portion, the flange having a rim extending abruptly inward at a right angle to the upper conical part and then extending downwardly 85 in a diverging conical form with the margin bent outwardly to form a bead, which rim is adapted to have a friction locking engagement with a substantially straight-walled jar top solely by downward pressure on the top of the closure without 90 reformation of the closure, the flange being provided with an outwardly extending annular portion adjacent the inwardly projecting rim portion, and a comparatively thin gasket of compressible sealing material held 95 in the closure by the rim, which is compressed on application of the closure to entirely fill the space between the jar side and top and the flange side and top portion above the rim.

CHARLES HAMMER.
